United States Patent Office.

WILLIAM H. PAGE, OF NORWICH, CONNECTICUT, ASSIGNOR TO W. H. PAGE AND COMPANY.

Design No. 2,979, dated March 31, 1868.

DESIGN FOR AN ALPHABET OF LETTERS.

The Schedule referred to in these Letters Patent and making part of the same.

TO ALL WHOM IT MAY CONCERN:

Be it known that I, WILLIAM H. PAGE, of the town of Norwich, in the county of New London, and State of Connecticut, have invented or produced a new and original Design of Wood Letter for printing purposes, styled "Ionic Condensed," for letter-press printing; and I do hereby declare that the accompanying drawing is a full and exact representation of the same.

What I claim as new, and desire to secure by Letters Patent, is—

The design for a letter, as shown and described.

WM. H. PAGE.

Witnesses:

TIMOTHY PARKER,

JAMES T. MOWRY.
